LIPSTICK HOLDER OR SIMILAR ARTICLE

George A. McConnell, Sherman Oaks, Calif., assignor of one-half to Douglas C. Anderson, North Hollywood, Calif.

Application April 30, 1958, Serial No. 50,673

Term of patent 14 years

(Cl. D86—10)

FIG. 1.

FIG. 2.

FIG. 3.

FIG. 4.

FIG. 5.

I claim:

The ornamental design for a lipstick holder or similar article, as shown.
